UNITED STATES PATENT OFFICE.

WILL B. HULL, OF BUFFALO, NEW YORK.

GARBAGE-RECEPACLE.

Specification of Letters Patent. Patented Feb. 6, 1917.

1,215,026.

Application filed November 28, 1913. Serial No. 803,392.

To all whom it may concern:

Be it known that I, WILL B. HULL, a citizen of the United States of America, and residing at Buffalo, county of Erie, and 5 State of New York, have invented certain new and useful Improvements in Garbage- Receptacles, of which the following is a full, clear, and exact description.

My invention relates generally to garbage 10 receptacles, and more particularly to covered garbage receptacles which may be opened by foot power.

The general object of my invention has 15 been to provide a device which shall be simple and cheap to manufacture, and one which shall be strong and durable. Another object has been to provide a simple and inexpensive cover operating mechanism for the receptacle.

20 I have attained these objects by the device shown in the accompanying drawings, forming part of this specification, and in which like characters of reference indicate like parts throughout the several views, of 25 which:

Figure 1 is a sectional elevation of my device, taken on the center line thereof and shows, in dotted lines, the position of the parts of the device when the cover is open.

30 Fig. 2 is a side elevation, partly in section, showing a modified form of cover operating device.

Fig. 3 is a fragmentary sectional view of 35 a device similar to that shown in Fig. 2, and shows a modified form of operating rod.

In the drawings, 5 represents the outer container of my device which is preferably made of sheet steel and provided with a 40 bottom 6. The container is provided with feet 7, which are secured to the bottom 6 in any suitable manner. 8 is the cover of my device which is pivotally connected to the outer container 5 by means of the hinge 9. 45 The hinge 9 comprises a member 10 secured to the cover 8, and a member 11 secured to the outer container 5. The member 10 of the hinge is provided with an outwardly extending arm 12 to which the cover raising mechanism is attached.

50 Disposed beneath the bottom 6 is a foot lever 13, provided with a pedal 14 at its extreme outer end and pivotally secured at its inner end to a lug 15. This lug 55 may be punched from the material which forms the bottom 6, or may be made of a

separate piece of material and secured to the bottom or side of the container, as desired. 16 is an operating lever also disposed beneath the bottom 6 and is pivotally united 60 near its center to the foot lever 13 by means of the pivot pin 17. The outer end of the operating lever is pivotally united with an operating rod 18 which connects the said lever with the arm 12 on the cover. 65 The inner end of the operating lever is curved somewhat and loosely disposed between the bottom 6 and a lug 19 secured thereto, whereby it is so held in position that a slight oscillating motion of the lever, 70 when operated, is possible.

20 is an inner container which fits inside the outer container 5 and is arranged to have a bead 21, formed at the upper edge thereof, rest upon the upper edge of the 75 outer container 5, thus preventing garbage or other refuse from getting into the outer container. This inner container is provided with a suitable bail 22 by which it may be easily handled and removed from, or placed 80 within, the outer container.

In the modification shown in Fig. 2, the outer container 23 is bottomless and is not provided with feet. The bottom edge of the material forming the outer container extends 85 to the floor-line and provides a suitable support for the same. In this form of device, the foot lever 24 is passed through a slot 25 formed in the lower part of the outer container and has its inner end pivotally connected to a suitable lug 26 secured to the inside of the outer container at the diametrically opposite side. The operating lever 27 has its inner end pivotally united by a pin 90 35 to a lug secured to the inside of the outer container, directly above the slot 25 and has its outer end passing through a slot 28 formed in the lower part of the outer container and preferably diametrically opposite to the slot 25. The levers 24 and 27 are 95 pivotally united near their centers by means of a pivot pin 29. The operating lever 27 is provided with a slot 30 in its inner end, in which the pivot pin 35 may move, thus 100 permitting a slight oscillating motion of the levers when operated. The outer end of the operating lever 27 is connected with the arm 12 of the cover 8 by means of an operating rod 31.

110 In Fig. 3, where I show a slightly modified form of operating rod, 32 is the outer container, which is provided in its lower

part with a foot lever 24, in a similar manner to the device just described, and an operating lever 33 which is pivoted to the side of the container and to the foot lever 24, 5 the same as just described in connection with the form shown in Fig. 2. A slot 34 is formed in the upper part of the container 32, directly beneath the hinge 9. The operating rod 35, in this form of the device, is 10 disposed within the outer container 32 and has its upper end bent at an angle and projecting through the slot 34.

Having thus described my invention, what I claim is:

- 15 1. A garbage receptacle comprising, an outer container, a hinged cover for said container, a cover operating mechanism located near the base of said container comprising, a foot lever extending diametrically across the bottom of said container and having one end pivotally secured to said container near the rear side thereof, while its other end extends beyond the front thereof, an operating lever extending diametrically across the bottom of said container and having one end loosely mounted on said container, means for pivotally uniting said operating lever and said foot lever near their centers, and an operating rod pivotally connecting the outer end of said operating lever and said cover, whereby said levers, when operated, have a shear like action.

20 2. A garbage receptacle comprising, an outer container, a cover, a hinge uniting said outer container and cover, said hinge being provided with an arm for limiting the backward motion of said cover, cover operating mechanism located near the base of said container comprising, a foot lever extending diametrically across the bottom of said con-

tainer and having one end pivotally secured to said container near the rear side thereof, while its other end extends beyond the front thereof, an operating lever extending diametrically across the bottom of said container and having one end loosely mounted on said container, means for pivotally uniting said operating lever and said foot lever near their centers, and an operating rod pivotally connecting the outer end of said operating lever and said cover, whereby said levers, when operated, have a shear like action. 45 50

3. A garbage receptacle comprising, an outer container, a hinged cover for said container, a cover operating mechanism located near the base of said container comprising, a foot lever extending diametrically across the bottom of said container and having one end pivotally secured to said container near the rear side thereof, while its other end extends beyond the front thereof, a strap secured to the lower part of said container, an operating lever extending diametrically across the bottom of said container and having its lower end slidably supported by said strap, means for pivotally uniting said operating lever and said foot lever near their centers, and an operating rod pivotally connecting the outer end of said operating lever and said cover, whereby said levers, when operated, have a shear like action. 55 60 65 70

In testimony whereof, I have hereunto signed my name in the presence of two subscribing witnesses.

WILL B. HULL.
